UNITED STATES PATENT OFFICE

GEORGE F. HARVEY, OF VICTORIA, BRITISH COLUMBIA, CANADA

TROLLING SPOON

Application filed October 31, 1928. Serial No. 316,310.

The present invention relates to trolling spoons and has for its principal object to provide an article of this character constructed of a pair of hingedly connected sections, arranged one in advance of the other so as to enable the rearmost hinged section to swing from side to side during the movement of the spoon through the water, substantially in imitation of the movement of 10 the tail of a fish.

A further object of the invention is to provide an article of this character, in which the rearmost hinged section is adapted to cause an irregular movement of the spoon 15 during its movement through the water and thus to closely imitate the wiggling movement of a fish.

Another object is to provide an attaching means for a hook along the rear edge of the 20 rearmost hinged section of the spoon providing for the vertical adjustment of the hook and through such adjustment to control the extent of the swinging movement of the rearmost hinged section.

An additional object is to provide a highly 25 efficient article of this character, which is capable of being produced in quantities at a relatively low cost and otherwise well adapted for the purpose for which the same 30 is intended.

Other objects and advantages reside in the special construction, combination and arrangement of the various elements forming the invention as more fully hereinafter 35 described and claimed, reference being had to the accompanying drawings forming part hereof, wherein like numerals refer to like parts throughout, and in which:

Figure 1 is a plan view of the device,

Figure 2 is a side elevational view showing the rearmost hinged section, or tail swung to an angular position,

Figure 3 is a plan view of the tail section,

Figure 4 is a group perspective view of 45 the pair of hinged sections constituting the invention,

Figure 5 is a vertical transverse sectional view taken substantially along the line 5—5 of Figure 1,

Figure 6 is a similar view taken substan-

tially along the line 6—6 of Figure 1, and Figure 7 is a fragmentary sectional view taken along the line 7—7 of Figure 1.

Referring now to the drawing in detail, for the purpose of illustration I have disclosed a preferred embodiment of the invention which comprises a trolling spoon of substantially oval shaped formation and constructed of a pair of hingedly connected sections 5 and 6 respectively.

The hinged section 5 is disposed forwardly and has its forward end formed with an opening 7 for receiving a ring 8 whereby to attach the usual swivel 9 and to which the fish line is connected. The rear edge of the 65 rear section 6 is also provided with a series of openings 10 for likewise receiving a ring 11 and to which the fish hook 12 is attached.

Each of the sections 5 and 6 is constructed 70 of sheet material, preferably highly polished light weight metal and disposed in end to end relation, with the abutting ends of the respective sections cut at an acute angle as shown at 13.

An opening 14 is formed in the section 5 adjacent the forward end of its inclined edge and a similar opening 15 is also formed adjacent the rear end of the inclined edge of the rear section 6.

The edges of the opposed sections, adjacent each of said openings, are formed with projections 16 and 17 respectively, each of said projections being bent in the shape of eyes 18, as clearly illustrated in Figures 5 and 7 of the drawings to provide a hinged 85 connection with the openings of the respective sections.

By reason of such hinged connection, it will be apparent that the rear section 6 is adapted to freely swing laterally with respect to the forward section 5, during the movement of the spoon through the water. A pair of lugs 19 are secured at the inclined edge 13 of the forward section 5 and form stops for engagement with the edges of the 95 rear section 6 whereby to limit the swinging movement of said rear section, in either direction, beyond a position at right angles to the forward section.

The manner in which these stop members 100

19 operate to restrict the swinging movement of the rear section, is clearly illustrated in Figure 6 of the drawings.

It will be readily appreciated from the foregoing that upon the movement of the spoon through the water that the idle swinging movement of the rear section 6 will cause the spoon to travel in an irregular course closely simulating the movement of a fish.

10 The freedom of the swinging movement of the rear section 6 may be controlled by the adjustment of the ring 11 in the various openings 10 provided for that purpose.

11 It is obvious that my invention is susceptible of various changes and modifications in construction without departing from the spirit of the invention or the scope of the appended claims, and I accordingly claim all such forms of the device to which I am entitled.

20 Having thus described my invention, what I claim as new is:

1. A trolling spoon comprising a plurality of sections of sheet material disposed in edge to edge relation and with their abutting edges inclined from the longitudinal center line and including a forward section and a tail section and means hingedly connecting said inclined edges of the sections at predetermined points to cause the tail sections to normally lie perpendicularly by gravitation.

25 2. A trolling spoon comprising a plurality of sections of sheet material disposed in edge to edge relation and with their abutting edges inclined from the longitudinal center line, means hingedly connecting the sections to each other and stop means formed on one of the sections and engageable with the opposite sides of the other of said sections whereby to limit the swinging movement of either of the sections with respect to each other.

30 In testimony whereof I affix my signature.
GEORGE F. HARVEY.
